Patented Dec. 8, 1908.

UNITED STATES PATENT OFFICE.

JOHN WRIGHT, OF POLLOKSHIELDS, SCOTLAND.

MACHINERY FOR CALENDERING LINOLEUM AND LIKE FABRICS.

No. 906,179.

Specification of Letters Patent.

Patented Dec. 8, 1908.

Application filed April 10, 1908. Serial No. 426,280.

To all whom it may concern:

Be it known that I, JOHN WRIGHT, a subject of the King of England, and resident of Pollokshields, Scotland, have invented Improvements in Machinery for Calendering Linoleum and Like Fabrics, of which the following is a specification.

For calendering inlaid linoleum whether the linoleum material be laid upon the backing in tiles of small or large size, or be in granulated form, machinery in which the material and backing pass between and are directly acted upon by calendering rolls is unsatisfactory, in that what may be termed the progressive squeezing action of the rolls tends to contort or displace the material upon the backing.

This invention has for its object to provide a simple and effective step-by-step calendering machine in which during the pressing operation the material and backing are held between plates—the distortion referred to being thus avoided. Such a machine although specially applicable in the manufacture of linoleum of the kind referred to is also of advantage for certain other analogous calendering purposes.

A machine made according to the invention comprises essentially a pair of pressing plates, the one below, the other above the linoleum fabric and adapted to transmit pressure to it. These plates are so guided as to be reciprocable between a pair of pressing rolls or cams. In operation, the linoleum fabric is moved forward step-by-step, and at each step, the plates are passed between the pressing rolls or cams, so pressing that part of the fabric which is between them at that time.

The improved machine is shown in side elevation on an accompanying sheet of explanatory drawings, to be hereinafter referred to in particularly describing the invention.

As shown in the drawing, the machine comprises two parallel and comparatively long side frames, A. Between these at one end is arranged a feeding drum, A¹, of considerable size. Onto this drum the fabric, B, to be pressed is led by guide rollers, B¹, B². From the upper surface of the drum, A¹, the fabric passes between a pair of pressing plates, C¹, C². Brackets, D, extending upwardly from each end of the upper pressing plate, C¹, carry rollers, D¹, which during the backward movement of the plates, as

hereinafter described, run upon horizontal guide rails, D², carried along the inner side of each side frame, A. The lower plate, C², is suspended from the upper plate by being secured to the lower end of headed bolts, E, passing freely through apertures in the upper plate and in strengthening bars, E¹, extending between the brackets, D, on each side of the upper surface of upper plate, the length of the bolts, E, being such that when the plates, C¹, C² are not being acted on by pressing rolls, as hereinafter described, the lower plate falls by its own weight sufficiently to allow the fabric, B, to pass freely between the plates.

The race for the pressing plates, C¹, C² extend between a pair of pressing rolls, G¹, G², carried in fixed bearings on the framing, A, the upper roll, G¹, being cylindrical, while the lower roll, G², is cam-shaped so that the pressing plates are nipped between the rolls for a certain proportion of each revolution.

Preferably both rolls, G¹, G², are driven through gearing (not shown) from any suitable source of power, and when their surfaces engage the plates, C¹, C², they carry them through the rolls, effectively pressing the portion of the fabric, B, which is then between them, this forward movement of the pressing plates, carrying the fabric through the machine. In the drawings, though the rolls are shown at the beginning of their action on the plates, the latter are left slightly apart in order to show the parts clearly. When the plates have passed the rolls, the lower plate, C², drops, freeing the fabric; and as the part of least diameter on the lower roll is then uppermost, the space between the rolls is then sufficient to allow the two plates to be moved back in their open position through the rolls to engage a fresh part of the fabric on their next forward movement. The plates, C¹, C² may be moved back in this manner by hand; but preferably this movement is effected mechanically by means of a pin, H, working in a slot, H¹, in one end of a lever H², fixed on a short shaft, J, capable of rocking in bearings in one of the side frames, A. On the shaft, J, is also secured a pawl lever, J¹, and from the end of the trunnion of the lower roll G², there projects a pin, J², so positioned, that when the pressing plates, C¹, C², are to be moved back, the pin, J², encounters and raises the outer end of the pawl lever, J¹. This movement rocks the shaft, J, and consequently also moves back the upper end of the lever,

H², which in turn, pulls back the plates, C¹, C², the carrying rollers, D¹, of these plates then running upon the horizontal guide rails, D², as hereinbefore described. During the 5 forward movement of the plates, the pin, J², moves out of contact with the end of the lever, J¹, so that the upper end of the lever, H², is free to move forward with the plates, and the outer end of the lever, J¹, is also then 10 lowered into the position in which it is in the way of the pin, J², when the next backward movement of the plates is to be effected.

From between the plates, C¹, C², the fabric, B, passes over and under guide rollers, K¹, K², to a take-up roll or beam, K, arranged 15 between the side frames, A. The roller, K², is arranged in vertical slots so that its weight acts to tension the fabric and at the same time permit of slight irregularity of the take-up motion. The roll, K, is rotated in known 20 manner by a modification of the well known variable take-up motion consisting of a disk, K³, on the axle of the roll, and rotated by frictional contact of a pulley, K⁴, carried by a 25 sleeve, K⁵, on a vertical shaft, K⁶, intermittently rotated as hereinbefore described. On a collar on the sleeve, K⁵, is a pin, K⁷, engaging the forked end of a lever, L, on a horizontal shaft, L¹, a second lever on which 30 engages with the spindle of a roller, L², bearing on the surface of the fabric, B, wound on the beam, K, so that the position of the pulley, K⁴, and consequently the rotation of the beam depends on the quantity of fabric on 35 the latter, thereby insuring a uniform take-up of fabric. On the lower end of the vertical shaft, K⁶, is a bevel pinion, M, gearing with a bevel wheel, M¹, on one end of a horizontal shaft, M², on the opposite end of which 40 is a pinion, M³, gearing in turn with a bevel wheel, N, fitted with a ratchet and pawl N¹, operated by a connecting rod, N², connected to the lower end of the lever, H², the ratchet being so set that the vertical shaft, K⁶, and 45 consequently the take-up roll, K, is intermittently rotated only at each forward movement of the pressing plates, C¹, C².

Preferably, the take-up mechanism is only sufficient to tension the fabric, that is, the 50 fabric is not independently driven—it is carried through the machine by the movements of the pressing plates. It may, however be moved independently. When, as hereinbefore described, it is not moved independently, 55 it is clear that what may be termed the successive areas of pressing performed by the plates, C¹, C², would only just join; consequently there would be great risk of markings between them.

60 In order to make the pressed areas overlap and obviate this, the feeding drum, A¹, over which the fabric passes upon its entry into the machine, is rotated a few degrees backwards carrying with it the fabric during each 65 return movement of the plates, the bearing of

the lower guide roll, K², being elongated to permit of this backward movement. This movement may very conveniently be brought about by a friction pawl, P, engaging a drum, P¹, fixed on the axle of the feeding drum, A¹, 70 a rod, P², connecting the pawl with the upper portion of the lever, H², so that the pawl, P, is made to engage with the drum, P¹, only on the backward movement of the pressing plates, C¹, C², when the fabric, B, is free to be 75 moved back by the backward movement of the feeding drum, A, thus effected.

Having fully described my invention, what I claim and desire to secure by Letters Patent is:—

1. A machine for calendering linoleum and the like fabric, comprising in combination, a pair of pressing plates (C¹, C²) brackets (D) on each end of the upper pressing plate (C¹), rollers (D¹) in said brackets, guide rails (D²) 80 on which said rollers run, pressing rolls (G¹, G²) carried in bearings on the frame, the lower roll being cam shaped so that during part of a revolution, the pressing plates are nipped together while the fabric is moved 85 forward, substantially as described and shown, and for the purpose set forth.

2. A machine for calendering linoleum and like fabrics, comprising in combination, a pair of pressing plates (C¹, C²) brackets (D) 90 on each end of the upper pressing plate (C¹), rollers (D¹) in said brackets, guide rails (D²) on which said rollers run, the lower plate (C²) being suspended from the upper (C¹), bolts 95 (E) in the upper plate passing through holes 100 in the lower plate (C²) so that the latter is free to fall away from said upper plate, to allow the fabric to pass freely between said plates, guide rollers (B¹, B²) leading said fabric, pressing rolls (G¹, G²) mounted in the machine frame, the lower roll (G²) being cam shaped, said rolls being driven from a suitable source of power, so that when they seize the plates (C¹ and C²) the latter nip the fabric and are carried forward with it, a 105 short shaft (J) rocking in bearings, a lever (H²) fixed on said shaft, said lever having a slot (H¹) at one end, a pin (H) on said plate (C¹) engaging in said slot, a pawl lever 110 (J¹) on said shaft, a pin (J²) on the end of the lower roll (G²), which engages with the said lever (J¹) when the said plates (C¹, C²) are to be moved back, a take up roll (K), 115 guide rollers (K¹, K²) for said fabric, a known type of take up motion, a bevel wheel (M) on the lower end of the vertical shaft of said take up motion, a horizontal shaft (M²), a bevel wheel (M¹) on said shaft, a pinion (M³) at the other end of said shaft, a bevel wheel 120 (N) in gear with said pinion, a pawl and ratchet (N¹) a connecting rod (N²) connected to lower end of said lever (H²), said ratchet being so set that the shaft of the take up motion is intermittently rotated at each forward 125 movement of the pressing plates, substan-

130

tially as described and shown, and for the purpose set forth.

3. A machine for calendering linoleum and like fabrics, comprising in combination, 5 a pair of pressing plates (C¹, C²), brackets (D) on each end of the upper pressing plates (C¹), rollers (D¹) in said brackets, guide rails (D²) on which said rollers run, the lower plate (C²) being suspended from the upper (C¹), bolts 10 (E) in the upper plate passing through holes in the lower plate (C²) so that the latter is free to fall away from said upper plate, to allow the fabric to pass freely between said plates, guide rollers (B¹, B²) leading said 15 fabric, pressing rolls (G¹, G²) mounted in the machine frame, the lower roll (G²) being cam shaped, said rolls being driven from a suitable source of power, so that when they seize the plates (C¹ and C²) the latter nip the 20 fabric and are carried forward with it, a short shaft (J) rocking in bearings, a lever (H²) fixed on said shaft, said lever having a slot (H¹) at one end, a pin (H) on said plate (C¹) engaging in said slot, a pawl lever (J¹) 25 on said shaft, a pin (J²) on the end of the lower roll (G²), which engages with the said lever (J¹) when the said plates (C¹, C²) are to be moved back, a take up roll (K), guide rollers (K¹, K²) for said fabric, a known type

of take-up motion, a bevel wheel (M) on the 30 lower end of the vertical shaft of said take up motion, a horizontal shaft (M²), a bevel wheel (M¹) on said shaft, a pinion (M³) at the other end of said shaft, a bevel wheel (N) in gear with said pinion, a pawl and ratchet 35 (N¹), a connecting rod (N²) connected to lower end of said lever (H²), said ratchet being so set that the shaft of the take up motion is intermittently rotated at each forward movement of the pressing plates, a 40 drum (P¹) on the feeding drum, a friction pawl (P) engaging with said drum (P¹), a rod (P²) connecting said pawl with the upper portion of the lever (H²), so that the pawl (P) engages with the drum (P¹) only on the backward movement of the pressing plates, when the fabric is free to be moved backwards by the backward movement of the feeding drum, substantially as described and shown, and 45 for the purpose set forth.

In testimony whereof I have hereunto set my hand in the presence of two subscribing witnesses.

JOHN WRIGHT.
